UNITED STATES PATENT OFFICE.

MARY C. BURKE, OF MONTPELIER, IDAHO.

WASH-BOARD.

SPECIFICATION forming part of Letters Patent No. 475,663, dated May 24, 1892.

Application filed February 27, 1891. Serial No. 383,075. (No model.)

To all whom it may concern.

Be it known that I, MARY C. BURKE, a citizen of the United States, residing at Montpelier, in the county of Bear Lake and State of Idaho, 5 have invented certain new and useful Improvements in Wash-Boards; and I do hereby declare that the following is a full, clear, and exact description of the invention, which will enable others skilled in the art to which it app-10 pertains to make and use the same.

My invention relates to wash-boards, and has for its object to provide a simple and improved wash-board which will possess advantages in point of inexpensiveness, durability, 15 ease of operation, and general efficiency.

To this end my invention consists, substantially, in a wash-board having a rubbing-surface composed of chain fabric, the links or rings which are adapted to move under the 20 pressure of the articles being rubbed when the wash-board is in use, whereby the wash-board is adapted to thoroughly rub the articles in a very short time and with great efficiency.

25 My invention further consists in certain details in the construction and arrangement of parts, substantially as hereinafter fully described, and particularly pointed out in the claim.

30 In the accompanying drawings, which illustrate my invention, Figure 1 is a perspective view of my improved wash-board. Fig. 2 is a sectional view of the same. Fig. 3 is a sectional view illustrating a modification.

35 In the upper end of the wash-board may be provided the usual soap-receptacle A, from which depend the sides B, the lower ends of which form the legs C. The sides B are connected at a suitable distance from their lower

40 ends by a cross-bar D, and hence the sides, cross-bar, and soap-receptacle constitute a rectangular frame, over which is stretched a rubbing-surface E, which comprises a chain fabric composed of circular links F, which

45 are intermeshed, as shown. The circular links are arranged in vertical series, extending from the upper end of the rubbing-surface to the lower end thereof, and while the said series of links are intermeshed or looped 50 into engagement with each other each vertical series is also intermeshed with the vertical series on each side thereof, the result being

that while the entire rubbing chain fabric is stretched tightly on the wash-board each individual link or ring thereof is capable of in- 55 dependent vertical and lateral motion.

This construction is very advantageous, inasmuch as the individual links or rings move under the friction of the fabrics when the wash-board is in use and serve to very thor- 60oughly rub them, thus lessening the labor of rubbing the clothes and effecting the operation with maximum efficiency.

Another advantage gained by this construction is that owing to the friction between the 65 moving links or rings they are prevented from becoming rusted, thus not only avoiding the danger of discoloring the fabrics being washed, but also preserving the working or rubbing surface and enhancing its durability. 70

The chain fabric may have its edges attached to the four sides of the frame of the wash-board either by means of staples, nails, or screws, or by any other suitable means such as will suggest themselves to persons 75 skilled in this art.

My improved wash-board may be provided with the usual back board G, as shown in Figs. 1 and 2, for the purpose of strengthening the frame and providing a backing for 80 the chain fabric, or under some circumstances this back board may be entirely dispensed with, as shown in Fig. 3, the chain fabric being simply, tightly, and securely stretched and fastened within the rectangular frame, under 85 which construction and arrangement both surfaces of the chain fabric may be used.

I do not wish to be understood as limiting myself to the exact construction and arrangement of parts herein shown and specified, as 90 manifest modifications may be made, particularly in the frame or body of the wash-board, and I therefore reserve the right to all such modifications and variations as properly fall within the spirit and scope of my invention. 95

Having thus described my invention, I claim and desire to secure by Letters Patent of the United States—

As an improved article of manufacture, the herein-described wash-board having the rubbing-surface formed by the flexible wire chain fabric, substantially as set forth, stretched within the frame of the wash-board and secured thereto at its four sides, the fabric be-

ing relatively mounted above the bottom plane of the wash-board, so that the entire fabric is unsupported at the back, whereby the connected links composing the flexible metallic fabric are adapted to individually move under pressure of the articles of clothing rubbed against the same in the operation of washing, while the fabric as an entirety offers flexible resistance against pressure in-

wardly in the operation of washing, substantially as set forth.

In testimony whereof I affix my signature in presence of two witnesses.

MARY C. BURKE.
